(57) **CLAIM**

The ornamental design for a vehicle ceiling, as shown and described.

DESCRIPTION

FIG. 1 is a partial perspective view of the interior of a vehicle, having a vehicle ceiling comprising a plurality of repeating vehicle ceiling panels, in accordance with our new design; FIG. 2 is a top plan view of one of the vehicle ceiling panels which make up the vehicle ceiling of FIG. 1; and, FIG. 3 is an end view of one of the vehicle ceiling panels which make up the vehicle ceiling of FIG. 1, shown within a vehicle body, the opposite end view being a mirror image thereof.

Any parts shown in broken lines form no part of the claimed design.

1 Claim, 3 Drawing Sheets

FIG. 1
